HEAT-DRIED DETERGENT PROCESSES

Harold E. Feierstein, Creve Coeur, Raymond L. Liss, Kirkwood, and Leo J. Weaver, Creve Coeur, Mo., assignors to Monsanto Chemical Company, St. Louis, Mo., a corporation of Delaware
No Drawing. Filed Mar. 14, 1961, Ser. No. 95,487
11 Claims. (Cl. 252—138)

This invention relates to methods for preparing heat-dried detergent compositions containing sodium tripolyphosphate. More particularly, this invention relates to improved processes for preparing free-flowing heat-dried detergent compositions containing hydrated sodium tripolyphosphate, which improved processes are substantially free of some of the difficulties that are inherent in conventional heat-drying processes.

Conventionally, heat-dried detergents containing sodium tripolyphosphate are made by first preparing a fluid mixture of water, detergent substances (surface active agents), and usually certain inorganic salts (such as sodium sulfate, tetrasodium pyrophosphate, sodium carbonate, etc.), adding sodium tripolyphosphate to this mixture, allowing the sodium tripolyphosphate to hydrate and subsequently heat-drying the resulting slurry either by spray-drying or by drying on a heated steel roll.

Experience has shown, however, that the manufacture of heat-dried detergents containing more than a few weight percent of sodium tripolyphosphate is beset with problems, most of which have not heretofore been readily overcome.

For example, with respect to the hydration of sodium tripolyphosphate contained in his slurries, the detergent manufacturer has heretofore been limited to only two basically different processes for the preparation of detergent slurries particularly if the detergent is to be heat-dried by spraying; i.e., he can either (1) hydrate the sodium tripolyphosphate in the slurry before it is heat-dried, or he can (2) heat-dry the slurry before the sodium tripolyphosphate has been substantially hydrated. No matter which of these processes the manufacturer utilized prior to this invention, there were certain inherent shortcomings in the process he chose. Thus, if the manufacturer chose to dry his slurry before the sodium tripolyphosphate was substantially hydrated, unpredictable changes in the viscosity of the slurry, effected by the still-hydrating sodium tripolyphosphate, often resulted in inadequate control of the rate at which the detergent slurry was dried, which, in turn often resulted in either incompletely dried or over-dried and sometimes scorched detergent product. The problem of controlling the viscosity of detergent slurries that contain actively hydrating sodium tripolyphosphate has been a particularly difficult one due to the many factors that can effect the rate at which the tripolyphosphate hydrates (such as the crystalline form of tripolyphosphate, the moisture content of the tripolyphosphate, the type of organic detergent active material present in the slurry, the amount of "seed" crystals of sodium tripolyphosphate that remained in the crutcher from the last previous batch of slurry, etc.). Additionally, unless the sodium tripolyphosphate had been substantially hydrated before the detergent slurry was dried, the resulting detergent product almost invariably became lumpy, caked readily after it was packaged, and was therefore not of a sufficiently good physical quality to sell to the consuming public. Conversely, if the detergent manufacturer did allow sufficient time to elapse (after the addition of the sodium tripolyphosphate to the "slurry") for the sodium tripolyphosphate to become substantially hydrated, a significant portion of the sodium tripolyphosphate generally underwent hydrolytic

2

cleavage, yielding equimolar quantities of orthophosphate and pyrophosphate, which are not as efficient as water softeners for detergents as is the tripolyphosphate.

The present invention makes it possible for the manufacturer of heat-dried detergents to produce a detergent product having excellent over-all physical properties, which product contains almost all of the sodium tripolyphosphate that was initially formulated into the detergent slurry in an undegraded state. An additional advantage of the present invention is that, by its practice, one can significantly increase the total capacity of existing slurry-crutching facilities without a proportional outlay of additional capital.

Another advantage of the present invention is that, by its practice, the total processing cost of producing spray-dried detergent can be reduced. Other advantages and objects of this invention will be readily apparent from the following description.

Briefly stated, the present invention, which is a new process for the preparation of heat-dried detergents, requires that at least two related acts be performed. First, sodium tripolyphosphate is substantially hydrated in an aqueous system that contains, at most, only a relatively small amount of organic detergent active material (often called the "surfactant"), and second, the remainder of the organic detergent active material is added to the detergent slurry only after the sodium tripolyphosphate has been substantially hydrated.

The invention is surprising because it was heretofore believed that in order to avoid the formation of hard, gritty lumps of an anhydrous sodium tripolyphosphate (covered with a layer of sodium tripolyphosphate hexahydrate), which lumps are difficult to eliminate from the formulation once they are formed, the organic detergent active material had to be mixed with the water in the detergent crutcher before the sodium tripolyphosphate was added. It has now been found that if the temperature of the water is sufficiently high when the sodium tripolyphosphate is added, the sodium tripolyphosphate can be mixed with the water and hydrated in the absence of at least the greater proportion of the organic surface active agent without the formation of the troublesome lumps described above.

If the sodium tripolyphosphate is hydrated in the absence of the greater portion of the organic detergent active materials, but in water, the initial temperature of which was generally above about 55° C., the troublesome, gritty lumps described above do not form. Thus, when one practices the tripolyphosphate hydration step according to this invention, then in order to produce the unexpectedly desirable detergent products which will result from practicing this invention one needs only to intermix the organic detergent active material with the tripolyphosphate after it has been substantially hydrated, and subsequently heat-dry the resulting mixture. When the initial water temperature is in the preferred range; that is, between about 65° C. and about 110° C.; only a minimum of agitation is necessary during the hydration of the sodium tripolyphosphate in order to attain a uniform, non-lumpy slurry. The phrases "initial temperature" and "initial water temperature" as utilized herein means the temperature of the water when the sodium tripolyphosphate is blended into it.

The initial temperature at which the water can be employed in the practice of this invention will depend to some extent upon the relative amounts of the low temperature and high temperature crystalline modifications in the sodium tripolyphosphate which is utilized for the formulations of the detergent slurry. Usually, for example, when more than about 20 weight percent of the sodium tripolyphosphate is the low temperature modifica-

tion or form, the initial water temperature should be below about 80° C. if relatively complete hydration of the sodium tripolyphosphate is desired. Otherwise, the initial water temperatures as high as 95° C. or even up to about 110° C. can be utilized so long as the temperature is not so high as to prevent the desired extent or degree of hydration of the sodium tripolyphosphate. However, it must be kept in mind that the initial water temperatures must always be at least high enough to prevent the formation of the above-described lumps.

The presence, in the water, of reasonable amounts of materials other than the organic detergent active materials (such as carboxymethylcellulose, silicates, sodium sulfate, sodium carbonate, tetrasodium pyrophosphate, etc.) when the sodium tripolyphosphate is added to the aqueous medium apparently has no detrimental effect upon the excellent results which can accrue to those who practice this invention.

Note that the terms "detergent slurry" and "anionic slurry" as utilized in the present specification and claims are each intended to mean a separate and distinct type of slurry. By "detergent slurry" is meant the slurry that exists during the first step in the processes of this invention; that is, a slurry which contains sodium tripolyphosphate and not enough organic detergent active ingredient to materially reduce the rate of hydration of the sodium tripolyphosphate (as compared to the rate of hydration of the tripolyphosphate in the absence of surfactant). Generally, the rate of hydration of the tripolyphosphate will not be materially reduced (i.e. by more than about 10%) so long as the "detergent slurry" does not contain more than about 10 weight percent (based on the weight of sodium tripolyphosphate present) of any organic detergent active material. Preferably, the "detergent slurry" will contain no more than about 5 weight percent of the organic detergent active material, and for optimum results, no more than a trace of the "surfactant." The term "anionic slurry" as is herein utilized encompasses those blends of some of the anionic surface active agents contemplated by this invention with water, and perhaps a diluent such as sodium sulfate, etc., which "anionic slurries" generally do not contain sodium tripolyphosphate. A typical "anionic slurry" that is commercially available today and widely used in the detergent industry contains about 54 weight percent of sodium dodecyl benzene sulfonate, about 4 weight percent of sodium sulfate, about 3 weight percent of sodium benzene sulfonate, and about 39 weight percent of water. Generally the "anionic slurries" contemplated herein will contain between about 30 and about 70 weight percent of water.

Because of the relatively high temperatures employed during the tripolyphosphate hydration step of the processes of this invention, one might ordinarily expect that the rate of hydrolytic degradation of the sodium tripolyphosphate would be relatively high (as compared with that of conventional low temperature hydration procedures). Surprisingly, however, the net result of practicing this invention is just the opposite. Apparently, the benefits (in the form of a significantly lower rate of hydrolytic degradation) which one achieves by excluding the organic surface active agents from the detergent slurry until after the tripolyphosphate is hydrated, combined with the increased rate of hydration of the tripolyphosphate (in the absence of the surface active agent), more than offset the potentially adverse effect of hydrating the tripolyphosphate at the relatively higher temperatures. Thus, by practicing this invention one can produce a heat-dried detergent product that contains considerably more of the sodium tripolyphosphate that was initially formulated thereto in an undegraded state than is presently possible using conventional processes to produce spray-dried detergents containing substantially hydrated sodium tripolyphosphate.

In order to produce detergent products having excel-

lent over-all functional and physical qualities according to this invention it is necessary that at least a major portion of the sodium tripolyphosphate contained therein be hydrated to the hexahydrate before at least the greater portion of the organic detergent active material is blended into the detergent slurry. Generally, for best results, at least about 75%, and preferably more than about 90%, of the sodium tripolyphosphate should be hydrated to the hexahydrate before it is blended with the greater portion of the surfactant. In the present specification and claims, the term "substantially hydrated," which is used with reference to the degree of hydration of the sodium tripolyphosphate, is intended to include any sodium tripolyphosphate, more than about 75% of which is in the form of the hexahydrate.

Ordinarily one can determine approximately the percentage of sodium tripolyphosphate in a given detergent slurry that has been hydrated at any given time after the addition of the sodium tripolyphosphate simply by measuring the viscosity of the slurry and comparing the viscosity actually measured with the maximum viscosity attained by a similar detergent slurry under similar conditions. The aforesaid maximum viscosity represents the viscosity of the slurry which contains completely hydrated sodium tripolyphosphate. The sodium tripolyphosphate in a given detergent slurry, then, is generally at least about 75% hydrated when the viscosity of the slurry containing the said sodium tripolyphosphate has increased to within about 10 percent of the maximum viscosity it will attain when completely hydrated under approximately the same conditions, while at least about 90% of the sodium tripolyphosphate in a given detergent slurry has been hydrated when the viscosity of the detergent slurry has increased to within about 5% of the maximum viscosity that the said detergent slurry will attain under approximately the same conditions. For example, when 50 parts of sodium tripolyphosphate are blended into 60 parts of water at an initial water temperature of 70° C., the apparent viscosity of the resulting slurry increases from about 150 centipoises to about 750 centipoises when 75% of the sodium tripolyphosphate is hydrated, to about 790 centipoises when 90% of the sodium tripolyphosphate is hydrated and to a maximum of about 800 centipoises when all of the sodium tripolyphosphate is hydrated.

Generally the sodium tripolyphosphate that is utilized in the practice of this invention will be substantially anhydrous; that is, it will usually contain less than about 5, and preferably less than about 2, weight percent (based on the anhydrous or dry weight of the sodium tripolyphosphate) of water, as water hydration. However, it is entirely practicable to practice the invention using sodium tripolyphosphate that contains up to about 10 weight percent, or even more, of water. As a practical matter, though, the sodium tripolyphosphate that is commercially available and least expensive will ordinarily be used. For example, the least expensive tripolyphosphate that is available today is "anhydrous" sodium tripolyphosphate, which usually contains between about 0.01 and about 1 weight percent of water. It is also preferred that the sodium tripolyphosphate that is utilized in the present invention be in the physical form which can be most readily dissolved in water and can be used in conventional detergent slurry processes, as for example, powder, flake, or light or medium density (e.g. up to about 0.9 gram per cubic centimeter) granular form.

All of the steps of this invention can be accomplished in practically any of the conventional detergent equipment presently being utilized in the industry. The only equipment that is essential for the hydration step, for example, is a container, fitted with means for heating and cooling its contents, and a fairly efficient mixer.

The term "organic detergent active material" is intended herein to encompass water-soluble organic surface active agents which are compatible with sodium tripoly-

phosphate. It is intended to include both the water-soluble anionic and the water-soluble nonionic classes of surface active agents.

The water-soluble anionic class of surface active agents includes such well-known materials as the higher alkyl (i.e. C_{10} to C_{20}) aryl sulfonic acids, and their alkali metal and alkaline earth metal salts (such as, for example, sodium dodecylbenzene sulfonate, sodium tridecylbenzene sulfonate, magnesium dodecylbenzene sulfonate, potassium tetradecylbenzene sulfonate, ammonium dodecyltoluene sulfonate, lithium pentadecylbenzene sulfonate, sodium dioctyl benzene sulfonate, disodium dodecylbenzene disulfonate, disodium diisopropyl naphthalene disulfonate, and the like); the alkali metal salts of fatty alcohol esters of sulfuric and sulfonic acids; the alkali metal salts of the alkylaryl (sulfothioc acid) ethers and the alkylthiosulfuric acids, etc.

The water-soluble nonionic class of surface active agents includes those produced by condensing one or more alkylene oxides, such as ethylene oxide or propylene oxide, with a relatively hydrophobic compound such as a fatty alcohol, fatty acid, glycerol, a fatty glyceride, a fatty amine, an arylamine, a fatty mercaptan, tall oil, etc.; and also includes those produced by condensing one or more relatively lower alkyl alcohol amines (such as ethanolamine, methanolamine, propanolamine, etc.), with a fatty acid such as lauric acid, cetyl acid, tall oil fatty acid, abietic acid, etc., to produce the corresponding amide; as well as any other water-soluble nonionic surface active agents that can be melted below about 300° C.

The actual physical manipulation of the materials (from which the final spray-dried detergent product is made) through the various stages or steps of the processes contemplated by this invention will depend to a considerable extent upon the physical form (e.g. solid, liquid, semi-solid, or water slurry) of the surface active agent (commonly termed "surfactant") which is to be utilized. For example, if the surface active agent is utilized in the form of a water-containing slurry, special consideration must be given to the amount of water contained in this surfactant slurry. But if the surfactant is utilized in the liquid form, or as a solid, certain other precautions should be observed if the detergent manufacturer wishes to produce the highest quality detergent product possible from his raw materials at reasonably low costs. It is because of these varying manipulative requirements with respect to the physical form of the surfactants that are utilized in the processes of the present invention that the following detailed discussion is subdivided into the groups: anionic-slurry, anionic-solid, anionic-liquid, nonionic-solid, nonionic-liquid.

ANIONIC-SLURRY

By far the greater majority of spray-dried detergents today contain as their major organic detergent active material, a sodium higher alkylaryl sulfonate. Almost invariably, this sodium higher alkylaryl sulfonate is formulated into the detergent composition (in the crutcher) as a water-containing slurry. Such sulfonate slurries usually comprise between about 30 and about 65 weight percent of the alkylaryl sulfonate, between about 30 and about 70 weight percent of water, and sometimes a few weight percent of sodium sulfate. The higher alkylaryl sulfonates are most widely used in the form of a slurry because it is in this form that they are most conveniently stored, shipped, and handled.

In order to maintain the detergent slurry at a reasonably low viscosity so that it can be pumped if desired from the crutcher to the drying facility, a certain amount of water in excess of that actually required to hydrate the sodium tripolyphosphate must be present in the detergent slurry throughout the entire crutting operation. Ordinarily this excess of water amounts to at least about one and one-half times, and preferably at least about two and one-half times, the weight of sodium tripolyphosphate in the detergent formulation. Of course, more than this

minimum amount of water can be utilized. However, as a practical matter, detergent slurries having more than about 45 weight percent of water are seldom heat-dried commercially because of the increase in production cost which results from the evaporation of the "excess" water during the heat-drying step.

Because the above-described minimum amount of water must be maintained through the hydration (of tripolyphosphate) step of the processes contemplated by this invention, and because the anionic slurries described heretofore will ordinarily not be combined with the remainder of the detergent slurry until sometime after the major portion of the sodium tripolyphosphate has been hydrated it can be seen that with certain formulations under certain conditions, limitations upon the total amount of sodium tripolyphosphate and/or the amount of anionic slurry which can be utilized in a given formulation will exist. For example, because of the minimum ratio of free water to tripolyphosphate which must ordinarily be maintained in the detergent slurry, one could not spray-dry a formulation such as that shown in Table I at a final detergent slurry "solids" (material that is not evaporated at 110° C.) concentration of 60 weight percent if the anionic slurry utilized therein contained no more than about 60 weight percent of "solids," unless the sodium tripolyphosphate content of the formula were reduced to less than about 30 parts.

Table I.—Formulation For Anionic Spray-Dried Detergent

Material:	Parts by weight
Sodium tripolyphosphate	50
Tetrasodium pyrophosphate	15
Sodium sulfate	20
Sodium carbonate	10
Sodium silicate (solids basis)	10
Sodium tridecylbenzene sulfonate	20

If, in the above example, the anionic slurry contains relatively fewer "solids" than 60% (i.e. more water), then still lower levels of the tripolyphosphate will have to be resorted to in order to maintain the desired 60% final detergent slurry "solids" concentration (immediately prior to the heat-drying step of the processes encompassed by this invention).

While it can be seen from the foregoing that in some instances when anionic slurries are utilized in the practice of this invention, special consideration must be given to the relative proportions of sodium tripolyphosphate, water, and surface active agent in the formulation, the considerations and calculations which must sometimes be made are nevertheless well within the abilities of anyone normally skilled in the art, and therefore should present no serious obstacle to anyone wishing to practice this invention.

Because of their physical form, the anionic slurries will ordinarily be pumped from storage to wherever they are utilized in the over-all detergent processes. Therefore, it is a relatively simple task to combine the anionic slurry with the detergent slurry (which contains the hydrated sodium tripolyphosphate) in any conventional manner that will yield a fairly uniform blend of the surface active agent with the other detergent ingredients before it is actually heat-dried. An extremely uniform blend of the two slurries will result, for example, if they are combined

on the inlet or exit side of the pump which, subsequently, moves the resulting final detergent blend to the spray nozzles. The anionic slurry can also be blended into the other detergent ingredients in the crutcher itself, after the sodium tripolyphosphate has been sufficiently hydrated.

One of the valuable results which can accrue to one who practices this invention, however, is that, when the anionic slurry is blended with the detergent slurry at some point after the detergent slurry is removed from the crutcher (for example, when it is being transported to

the drying facility), there will be an appreciable increase in the total capacity of the detergent plant (compared with that which resulted from the utilization of conventional processes in this same plant). Actually, if one practices this invention in one of the preferred manners, i.e. by blending the anionic slurry with the detergent slurry at some point after the detergent slurry has been removed from the crutcher, the minimum increase in total detergent plant capacity that one can achieve (as compared to the total plant capacity when conventional procedures are utilized), should be at least equal to the volume percent of anionic slurry that the detergent manufacturer includes in his formulation. For example, in a process in which prior to this invention, the anionic slurry represented about 30 volume percent of the materials charged into the detergent crutcher, the expedients by which this invention is practiced make it possible to increase the total capacity of this same plant by at least about 40%, or even more (30% by adding the anionic slurry after the other ingredients are removed from the crutcher, and an additional 10% or more due to the increased rate of hydration of the sodium tripolyphosphate in the crutting step).

One of the procedures for the utilization of anionic slurries according to this invention is illustrated in Example I.

EXAMPLE I

Into a detergent crutcher are charged the following ingredients (which, in this case, fill the crutcher to approximately its volume capacity).

Ingredients:	Pounds
Water	6860
Sodium silicate solution (containing 56% water)	1140
Sodium sulfate	3000
Tetrasodium pyrophosphate	1500
Sodium carbonate	500
Sodium carboxymethylcellulose	100
Optical bleach	9.6

The resulting blend is heated to 70° C., after which 3000 pounds of sodium tripolyphosphate (containing 60 weight percent of the low temperature crystalline form and 0.4 weight percent of water) is added over a six minute period of time. While being stirred for an additional 12 minutes, the temperature of the resulting detergent slurry rises to about 80° C. while its apparent viscosity (measured by the Bendix ultra-visicon) increases to approximately 800 units (from about 200 units before the sodium tripolyphosphate is added). The maximum viscosity that a detergent slurry of this formulation will attain under these conditions is about 865 units. Therefore, it can be seen that approximately 90% of the sodium tripolyphosphate in this detergent slurry is hydrated in about 12 minutes after the sodium tripolyphosphate is added to the crutcher.

As quickly as possible after the detergent slurry has reached an apparent viscosity of about 800 units, it is pumped from the crutcher through a flow-meter to a high pressure pump. Into this detergent slurry on the inlet side of the said high-pressure pump is injected an amount of an anionic slurry (composed of 52 weight percent of the sodium salt of dodecylbenzene sulfonic acid, 3 weight percent of sodium benzene sulfonate, 0.5 weight percent of sodium sulfate and 54.5 weight percent water) equal to 40 weight percent of the amount of the above-described detergent slurry (containing the substantially hydrated tripolyphosphate) which is being pumped into the said high-pressure pump. From the high-pressure pump, the resulting blend is transported to a conventional spraying facility, where it is spray-dried to yield a detergent product containing the following ingredients (anhydrous basis) in approximately the following amounts.

Ingredient:	Weight percent
Sodium dodecylbenzene sulfonate	22.4
Sodium cumene sulfonate	1.3
Sodium sulfate	27.0
Sodium carbonate	4.5
Sodium silicate	4.5
Tetrasodium pyrophosphate	13.4
Sodium tripolyphosphate	27.0
Sodium carboxymethylcellulose	1.0
Optical bleach	0.1

The total capacity of the plant that utilizes the above-described process, is thus, increased by at least 40 percent, as compared to the total capacity of the same plant that utilizes the conventional technique of hydrating the sodium tripolyphosphate in a crutcher which contains, in addition to the other detergent ingredients, the anionic slurry. When one also considers the effective increase in the rate at which the sodium tripolyphosphate hydrates when one practices the instant invention, it can be seen that the total capacity of the plant is increased still further. For example, in Example I, 90% of the sodium tripolyphosphate is hydrated in about 12 minutes after the tripolyphosphate is added to the crutcher. If the anionic slurry had been present in the crutcher before the tripolyphosphate was added, the sodium tripolyphosphate would have required at least about 30 minutes to hydrate to the same degree as that in Example I.

In order to demonstrate the benefits of the processes of this invention insofar as decreasing the degradation of the sodium tripolyphosphate (by way of hydrolysis, or "hydrolytic degradation") is concerned, one gram samples of detergent products, which have been spray-dried as soon as 90% of their sodium tripolyphosphate has been hydrated, are dissolved in 100 mls. of water. Then the pH of the resulting solutions is measured. Since the products from the degradation of sodium tripolyphosphate are acidic, the sample with the higher pH contains proportionately more undegraded tripolyphosphate than does the other sample. Note that the sample prepared according to this invention contains more undegraded sodium tripolyphosphate than that which is prepared via the conventional process of hydrating the tripolyphosphate in the presence of the surface active agent. Table 2 lists data from such a comparison.

Table 2.—Acidity of Heat-Dried Detergents

50	Detergent Process	Time to Hydrate, ¹ minutes	pH
As Example I Conventionally		12 35	9.2 8.6

55 ¹ Time for viscosity to reach 95% of peak viscosity for slurry.

ANIONIC-SOLID

Although the solid forms of the anionic surface active agents such as sodium pentadecylbenzene sulfonate, magnesium dodecylbenzene sulfonate, sodium octadecyl sulfate, sodium tetradecyl thiosulfate, and the like (often containing solid diluents such as urea, sodium sulfate, etc., blended therewith), are not so widely used conventionally in the preparation of spray-dried detergents as are the anionic slurries, they are used to some extent, and can also be used in the practice of this invention. Actually, the use of the solid anionic surface active agents according to this invention are advantageous in some respects over the use of the anionic slurries described heretofore, because their (solid anionics) use makes it possible to charge all of the water which is to be utilized in the formulation into the crutcher either prior to or during the hydration of the sodium tripolyphosphate, thus contributing to a substantial decrease in the viscosity of the

detergent slurry in the crutcher as well as a substantial decrease in the total power which is consumed in stirring the detergent slurry in the crutcher.

The solid anionic surface active agents can be blended with the detergent slurry at any time after most of the sodium tripolyphosphate has been hydrated, and in any convenient conventional mixing equipment. For example, in one plant, after the sodium tripolyphosphate has been hydrated for about 8-10 minutes, the detergent slurry is metered from the crutcher into a 30 gallon mixing vessel containing a 1 horsepower high-speed dual-propeller-type mixer. The solid anionic "surfactant" (85% sodium dodecylbenzene sulfonate + 15% sodium sulfate, in one instance) is also metered into the same mixing vessel, at a rate which results in the formation of a final slurry containing the proper ratio of anionic surface active agent to sodium tripolyphosphate that is desired in the final product. The average sojourn time in the said mixing vessel for the resulting slurry will vary, depending upon many factors which are well within the skill of those in the art to consider and control. Usually, however, the blending of the solid anionic "surfactant" and the detergent slurry should be done as quickly as possible, since, in order to minimize the hydrolytic degradation of the sodium tripolyphosphate, the final slurry should be heat-dried as soon as possible after the sodium tripolyphosphate has been hydrated.

ANIONIC-LIQUID

The water-soluble anionic surface active agents which are contemplated under this heading are those that do not contain substantially more than perhaps a trace of water; i.e., those, the natural physical form of which is liquid. Actually, the liquid anionic surface active agents which fall into this classification are almost solely the anionic surfactant acids, such as alkyl sulfonic acids, alkylaryl sulfonic acids, alkyl sulfuric acid esters etc. These acids are generally easy to handle and pump (especially when they are warm), are relatively inexpensive, are generally readily available commercially, and are very useful in the practice of this invention. The fact that many of the anionic surfactant acids contemplated herein are very viscous at room temperature is not a particularly important obstacle to their being utilized according to the processes of this invention, since, upon being warmed, their viscosity is invariably lowered to a point at which they can be pumped and, thus, readily handled in conventional equipment. Because the color of the anionic surfactant acids often degrades when they are held for extended times at extremely high temperatures without being neutralized, it is preferred that the temperature of these acids be maintained below about 200° C. and even more preferably, below about 75° C. at all times.

So far as the actual procedural requirements that must be met when the anionic surfactant acids are utilized according to this invention, the most important one is that at some stage in the processes prior to the formulation's actually being heat-dried, at least enough alkaline ingredients (usually one or more alkali metal- or alkaline earth metal-hydroxide or carbonate such as NaOH, KOH, LiOH, Na₂CO₃, Mg(OH)₂, Ca(OH)₂, MgCO₃ etc.), must be blended into the detergent slurry to neutralize the said anionic surfactant acids. For example, the said alkaline ingredients can be charged into the crutcher at any time prior to the discharge of the hydrated tripolyphosphate therefrom. Or the said alkaline ingredients can be injected into the system which is used to transport the detergent slurry to the spraying facility at any point along the way. If, for example, the detergent slurry and the anionic active are blended together in a separate mixing tank such as that described under the heading of "Anionic-Solid," above, the said alkaline ingredients can also be blended into the other slurry ingredients at the same time. It is preferred, however, that the said alkaline ingredients

be already present along with the hot water in the crutcher when the sodium tripolyphosphate is added thereto, since, thereby, the rate of hydration of the sodium tripolyphosphate is desirably increased.

While it is particularly desirable, when practicing this invention and utilizing the liquid anionic surfactants, that the alkaline ingredients heretofore described be well mixed with the water-soluble anionic acids before the final slurry blend is heat-dried, it is not essential that the said alkaline ingredients be present in the detergent slurry before the anionic surfactant acid is added. For example, it is possible to add the said alkaline ingredients to an already-prepared blend of the detergent slurry with the anionic surfactant acid a short time before the resulting slurry is heat-dried, and produce a detergent having all of the improved properties described heretofore.

Since, by their nature, the water-soluble anionic acids contemplated herein are liquids, they will ordinarily be pumped from storage to wherever they are to be utilized in the over-all detergent processes. These acids, just as their anionic slurry counterparts, can be combined with the detergent slurry in any conventional manner that will yield a reasonably uniform blend of the surface active agent with the other detergent ingredients before they are heat-dried. See, for example, the blending recommendations described under the heading of "Anionic-Slurry," above.

EXAMPLE II

Into a detergent crutcher are charged the following ingredients (which ingredients together represent approximately the volume capacity of the crutcher).

Ingredients:	Pounds
Water	6344
Sodium silicate solution (containing 60% water)	1429
Sodium sulfate	4949
Sodium hydroxide (containing 50% water)	278
Sodium carboxymethylcellulose	100
Optical bleach	9.6

The resulting blend is heated to 65° C., after which 2900 pounds of sodium tripolyphosphate (containing 75 weight percent of the low temperature crystalline form and 0.2 weight percent of water) is added over a six minute period of time. While being stirred for an additional 10 minutes, the temperature of the resulting detergent slurry rises to about 78° C. while its apparent viscosity increases to about 920 units (from about 150 units before the sodium tripolyphosphate is added). The maximum viscosity that a detergent slurry of this type will attain is about 980 units. Therefore, it can be seen that approximately 85% of the sodium tripolyphosphate in this detergent slurry is hydrated in about 10 minutes after the sodium tripolyphosphate is added to the crutcher.

The resulting detergent slurry is then pumped from the crutcher through a flow-meter to a high pressure pump. Into the detergent slurry on the exit side of the flow-meter is injected an amount of dodecylbenzene sulfonic acid (which has been previously warmed to a temperature of 60° C.) equal to 10.56 weight percent of the amount of the aforesaid detergent slurry which is being pumped to the high-pressure pump. From the pump, the resulting blend is transported through a conventional deaerator (to remove dissolved and entrapped air) to a conventional spraying facility, where it is spray-dried to yield a free-flowing, high quality detergent product which contains almost all of the sodium tripolyphosphate that was initially added to the detergent crutcher in an undegraded state.

Another advantage of the present invention can be seen by a consideration of the data in Table 3, in which is tabulated the power consumed in the above-described crutting operation compared with the power consumed

when conventional detergent crutching processes (with a similar detergent formulation) are utilized:

Table 3

Process	Time to Hydrate, ¹ minutes	Power Required, ² amperes
As in Example III Conventional.....	10 35	17 23

¹ Time required for slurry viscosity to reach 93% of maximum.
² Amount of current drawn to stir crutcher charge during hydration. Figure given is average for period of hydration shown.

Note that in Example II, above, even excluding from consideration the substantial beneficial effect of the increased rate of sodium tripolyphosphate, the process of this invention makes it possible to increase the plant capacity by at least 11 percent.

Similarly excellent results would result if the detergent slurry in Example II, above, had been blended with the sulfonic acid in a separate blending tank. For example, by continuously metering the above-described detergent slurry (which contains sufficient alkaline ingredients to neutralize the sulfonic acid) into a separate 50 gallon mixing tank fitted with a fairly efficient means for stirring, and also continuously metering an amount of the dodecylbenzene sulfonic acid equal to 10.6 weight percent of the said detergent slurry into the same mixing tank, allowing the resulting blend to remain in the mixing tank for a short period of time in order to become thoroughly intermixed, and finally continuously withdrawing from the mixing tank and spray-drying the well-mixed blend, a detergent product of similarly excellent qualities as that produced according to Example II can be made.

NONIONIC-SOLID

The physical form of relatively pure water-soluble nonionic surface active agents is usually either liquid or semi-solid (waxy), and only rarely "solid." However, certain of the reaction products or condensation-products of some of the nonionic surface active agents (notably the urea adducts of the nonionic "surfactants" that contain multiple alkylene oxide chains, for example) are distinctly solid in character and can be utilized in the practice of this invention much as can be the solid water-soluble anionic "surfactants" described hereinbefore.

EXAMPLE III

Into a detergent crutcher are charged the following ingredients.

Ingredients:	Pounds
Water	5262
Sodium silicate solution (containing 56% water)	2147
Sodium carbonate	504
Sodium sulfate	1313
Tetrapotassium pyrophosphate	900
Sodium carboxymethylcellulose	100
Optical bleach	9.6

The resulting blend is warmed to 90° C., after which 4548 pounds of sodium tripolyphosphate (containing 93 weight percent of the high temperature crystalline form and 0.3 weight percent of water) is added over a 5 minute period of time. While being stirred for an additional 8 minutes, the current drawn by the crutcher stirring motor increases to 17.5 amperes (from 12 amperes initially), which current of 17.5 amperes is about 95% of the maximum current drawn by a similar slurry when the sodium tripolyphosphate contained therein is completely hydrated, and thus, signifies that at least about 90 percent of said sodium tripolyphosphate has been hydrated (current drawn by the crutcher stirring motor during this operation is proportional to the viscosity of the detergent slurry being mixed in the crutcher).

The resulting detergent slurry is then pumped from the crutcher through a flow-meter, and into a 50-gallon conventional mixing tank containing a conventional impeller-type stirrer. Into the same mixing tank at a rate proportional to 7.58 weight percent of the said detergent slurry is metered a nonionic surface active agent in the solid state (composed of (a) 55 weight percent of a condensate of one mole of tridecyl alcohol with 12 moles of ethylene oxide and (b) 45 weight percent of urea). The rates at which the detergent slurry and the nonionic "surfactant" are poured into the mixing tank are controlled so that the resulting blend remains in the mixing tank for approximately 4 minutes (to dissolve the solid non-ionic ingredient), after which the blend is transported to a conventional spraying facility, where it is spray-dried to yield an excellent detergent product containing approximately the following ingredients.

Ingredient:	Weight percent
Water	5.0
Sodium silicate	10.0
Sodium carbonate	5.0
Sodium sulfate	13.0
Tetrapotassium pyrophosphate	8.9
Sodium tripolyphosphate	45.0
Sodium carboxymethylcellulose	1.0
Optical bleach	0.1
Nonionic surfactant	12.0

It is usually more desirable, however, to melt the non-ionic surface active agents contemplated by this invention if they are not already in the liquid state, and treat them according to the procedures described under the heading of "Nonionic-Liquid," below.

NONIONIC-LIQUID

Even though most of the nonionic surface active agents contemplated by this invention are either semi-solid or wax-like in physical form at room temperature, they can be readily melted and thereafter transferred from one location to another in any particular detergent plant by means of pumps and pipes. Generally, the nonionic surface active agents are less subject to a degradation of their color when they are heated than are the above-described anionic acids. However, it is generally preferred that the temperature of liquid nonionics be maintained at below about 200° C. if they are to be held at elevated temperatures for any extended period of time. Actually, a temperature of about 150° C. is sufficient to reduce the viscosity of almost all of the nonionic surface active agents contemplated by this invention to the point at which they are pumpable, and thus can be handled by conventional transferring, spraying and mixing equipment.

The liquid nonionic "surfactants" contemplated herein can be blended into the detergent slurry at any point in the detergent processes subsequent to the hydration of the sodium tripolyphosphate (described above), and in any manner which is convenient. For example, the liquid nonionic "surfactants" can be blended with the detergent slurry in practically the same manner as can the anionic slurries, described hereinbefore, either with or without additional water (to maintain the nonionic surface active agents in the "liquid" state).

EXAMPLE IV

Into a detergent crutcher are charged the following ingredients.

Ingredients:	Pounds
Water	6458
Sodium silicate solution (63% H ₂ O)	895
Sodium carboxymethylcellulose	110
Sodium carbonate	1874
Sodium sulfate	2217
Optical bleach	10.5
Tetrasodium pyrophosphate	2217

The resulting blend is warmed to 70° C., after which 2217 pounds (containing 60 weight percent of the low temperature modification) of sodium tripolyphosphate is added over a 4 minute period of time. While the resulting blend is agitated for an additional ten minutes, the current drawn by the crutcher stirring motor increases from about 10 to 17 amperes (which current of 17 amperes is approximately 95% of the maximum current which is drawn by a practically identical detergent slurry when the sodium tripolyphosphate contained therein is completely hydrated), indicating that within 10 minutes at least about 90% of the sodium tripolyphosphate has been hydrated. The resulting slurry (containing the substantially hydrated tripolyphosphate) is then pumped to the intake side of a high pressure pump, where it is blended with a warm (40° C.) blend of nonionic surface active agents in the liquid state at a rate proportional to 14 parts of the said blend of nonionic surface active agents per 20 parts of sodium tripolyphosphate (dry basis) in the detergent slurry.

The blend of nonionic surface active agents is composed of 50 weight percent each of a condensation product of one mole of nonylphenol with about 15 moles of ethylene oxide and a condensation product of 3 moles of propylene glycol with about 35 moles of ethylene oxide.

The rates at which the detergent slurry and the nonionic surfactant blend are transferred to the inlet side of the aforesaid high pressure pump are controlled so that all of the various ingredients in the resulting final slurry will have been thoroughly intermixed before they are heat-dried. The final slurry is pumped from the high pressure pump to a conventional spraying facility, where it is spray-dried to yield a detergent composition having excellent over-all physical and functional properties, and the following formulation.

Typical Formulation of Nonionic Heat-Dried Detergent

Ingredients:	Percent
Water	5.0
Sodium silicate	3.0
Sodium carboxymethylcellulose	1.0
Sodium carbonate	16.9
Sodium tripolyphosphate	20.0
Tetrasodium pyrophosphate	20.0
Alkylphenol+15 Eto	7.0
Propylene glycol—Eto condensate	7.0
Optical bleach	0.1
Sodium sulfate	20.0

What is claimed is:

1. In a process for producing a heat-dried built detergent wherein sodium tripolyphosphate is intermixed with a liquid aqueous medium containing an amount of water more than sufficient to hydrate said sodium tripolyphosphate to the hexahydrate, the improvement which comprises maintaining said aqueous medium free of an amount of organic detergent active material sufficient to materially reduce the rate of hydration of said sodium tripolyphosphate until at least a major portion of said sodium tripolyphosphate is transformed to the hexahydrate; said amount of organic detergent active material constituting at most about 10 weight percent of the resulting mixture; maintaining the temperature of said aqueous medium during said hydration between about 55° C. and about 110° C. to prevent the formation of lumps that otherwise would be formed by the hydrating sodium tripolyphosphate in the substantial absence of organic detergent active material, but not at so high a temperature as to prevent the hydration of said sodium tripolyphosphate, and thereafter intermixing with the resulting detergent slurry an organic detergent active material, and then heat-drying said slurry.

2. A process according to claim 1 wherein the initial temperature of said aqueous medium is at least about 65° C. and said hydration of said sodium tripolyphosphate is

effected at a temperature between about 65° C. and about 110° C.

3. A process according to claim 1 wherein the initial temperature of said aqueous medium is at least about 55° C., said hydration of said sodium tripolyphosphate is effected at a temperature between about 55° C. and about 80° C., and at least about 20 weight percent of said sodium tripolyphosphate is the low temperature crystalline form.

4. A process for the preparation of a heat-dried detergent composition containing a water-soluble synthetic anionic surface active agent, which process comprises the steps of first intermixing sodium tripolyphosphate with a liquid aqueous medium containing an amount of water equal to at least about 1½ times the weight of said sodium tripolyphosphate, maintaining said aqueous medium free of an amount of said synthetic anionic surface active agent sufficient to materially reduce the rate of hydration of said sodium tripolyphosphate; said amount of said synthetic organic detergent active material constituting at most about 10 weight percent of the resulting mixture; and maintaining the aqueous medium at a temperature between about 55° C. and about 110° C. until at least about 75 weight percent of said sodium tripolyphosphate is transformed to the hexahydrate, whereby said hydration is effected at a rapid rate and with low degradation of said sodium tripolyphosphate without the formation of lumps, and thereafter intermixing with the resulting detergent slurry said water-soluble anionic surface active agent and then heat-drying said slurry.

5. A process for the preparation of a heat-dried detergent composition containing a water-soluble synthetic anionic surface active agent and sodium tripolyphosphate, which process comprises the steps of first intermixing at an initial temperature between about 55° C. and about 80° C. said sodium tripolyphosphate; said tripolyphosphate initially containing at least about 20 weight percent of the low temperature crystalline modification; with a liquid aqueous medium containing an amount of water more than sufficient to convert said sodium tripolyphosphate to the hexahydrate, maintaining the temperature of said aqueous medium between about 55° C. and about 80° C., and also maintaining less than about 5 weight percent, based on the weight of said sodium tripolyphosphate, of said synthetic anionic surface active agent in said aqueous medium until at least about 75% of said sodium tripolyphosphate is transformed to the hexahydrate; and thereafter intermixing with the resulting detergent slurry said water-soluble anionic surface active agent and then heat-drying said slurry.

6. A process for the preparation of a heat-dried detergent composition that contains a water-soluble higher alkylbenzene sulfonate, which process comprises the steps of first intermixing sodium tripolyphosphate, which contains between about 0 and about 10 weight percent of moisture, with a liquid aqueous medium which contains an amount of water equal to at least about 2½ times the weight of said sodium tripolyphosphate at an initial temperature between about 65° C. and 110° C.; said liquid aqueous medium also containing an alkali metal hydroxide selected from the group consisting of sodium hydroxide, potassium hydroxide, and lithium hydroxide; maintaining the temperature of said aqueous medium between about 65° C. and about 110° C. and maintaining said aqueous medium substantially free of any organic detergent active material until at least about 90% of said sodium tripolyphosphate is transformed to the hexahydrate; and thereafter intermixing with the resulting detergent slurry a quantity of water-soluble higher alkylbenzene sulfonic acid and then heat-drying said slurry.

7. In a process for the preparation of a heat-dried detergent composition containing a water-soluble synthetic nonionic surface active agent in which process sodium tripolyphosphate is intermixed with a liquid aqueous medium containing an amount of water more than

15

sufficient to hydrate said sodium tripolyphosphate to the hexahydrate, the improvement which comprises maintaining the temperature of said aqueous medium at a temperature between about 55° C. and about 110° C., and maintaining the level of said synthetic nonionic surface active agent in said aqueous medium below about 5 weight percent until at least about 75% of said sodium tripolyphosphate is transformed to the hexahydrate, and thereafter intermixing with the resulting detergent slurry said water-soluble nonionic surface active agent and then heating and drying said slurry.

8. A process as in claim 5, wherein said water-soluble anionic surface active agent is sodium dodecylbenzene sulfonate.

9. A process as in claim 5, wherein said water-soluble

16

anionic surface active agent is sodium tridecylbenzene sulfonate.

10. A process as in claim 6, wherein said water-soluble higher alkylbenzene sulfonic acid is dodecylbenzene sulfonic acid.

11. A process as in claim 7, wherein said water-soluble nonionic surface active agent is a condensation product of nonylphenol with ethylene oxide.
